(57) **CLAIM**

The ornamental design for a food containing plate, as shown and described.

DESCRIPTION

FIG. 1 is a perspective view showing a food containing plate according to my new design;

FIG. 2 is a front elevational view thereof, the opposite side being a mirror image;

FIG. 3 is a side elevational view thereof, the opposite side being a mirror image; and,

FIG. 4 is a top plan view thereof.

For clarity, the food containing plate is shown within a black background environment that forms no part of the claimed design.
